FEED THROWOUT MECHANISM FOR
SEWING MACHINES

Robert L. Hoffmeister, Helensburgh, Scotland,
assignor to The Singer Manufacturing Company,
Elizabeth, N. J., a corporation of New Jersey

Application April 15, 1953, Serial No. 348,897

5 Claims. (Cl. 112—210)

1

The present invention relates to sewing machines and has for a primary object to provide a new and improved feed throw-out mechanism for a sewing machine.

More specifically, it is an object of the present invention to provide a new and improved feed throw-out mechanism which is of simplified construction and thus more economical, and one which is more readily accessible and easier to operate so that it may be more conveniently actuated to effect feed throw-in or throw-out. Further, it is an object of this invention to provide a feed throw-out mechanism which is efficient and thoroughly dependable in operation.

Having in mind the above and other objects that will be evident from an understanding of this disclosure, the invention comprises the devices, combinations and arrangements of parts as illustrated in the presently preferred embodiment of the invention which is hereinafter set forth in such detail as to enable those skilled in the art readily to understand the function, operation, construction and advantages of it when read in conjunction with the accompanying drawings in which:

Fig. 1 is a bottom plan view of a sewing machine in which a throw-out mechanism in accordance with the present invention has been incorporated in the feed-lift mechanism.

Fig. 2 is a fragmentary section view taken substantially on the line 2—2 of Fig. 1.

Fig. 3 is a fragmentary section view taken substantially on the line 3—3 of Fig. 1.

Fig. 4 is a section view taken substantially on the line 4—4 of Fig. 1.

Fig. 5 is a fragmentary section view similar to Fig. 2 but with the feed-drive in throw-out position and with parts broken away to illustrate more clearly the mechanism lying behind the same.

The present invention is illustrated as embodied in a sewing machine similar to that disclosed in the patent of Eames, No. 2,024,434, and having a bed 1 provided with the usual throat plate 2. Journaled longitudinally of the bed 1 in suitable lugs 3 and 4 depending from the bed is a rotary shaft 5. At one end the shaft 5 carries a pulley 6 about which is entrained a belt 7. Although not illustrated, the belt 7 may be driven from a belt pulley fixed to the usual bracket-arm shaft which, in turn, may be driven by a belt-driven pulley as illustrated in the above Eames patent. Thus rotation is delivered to the shaft 5.

The end of the shaft 5 opposite to that end

2

carrying the pulley 6 is fitted into a bore formed in a loop-taker housing 8 and is journaled in a suitable bushing 8a provided in the lug 3 and extending into the housing 8. The housing 8 is provided with a laterally extending flange 9 (Fig. 1) that is secured to the under side of the bed 1 by a screw 10, which, together with the bushing 8a, constitutes the sole support for the housing 8. A horizontal transverse bore is provided in the housing 8, in which bore there is journaled the loop-taker shaft 11 having a loop-taker in the form of a rotary hook 12 fixed to one end thereof. Within the housing 8, the shaft 11 has secured thereto a gear 13 that meshes with a gear 14 fixed to the end of the shaft 5. In the usual manner the ratio between the gears 13 and 14 is 2:1 whereby the loop-taker shaft 11 will be driven at twice the speed of the shaft 5. The gears 13 and 14 may be lubricated by packing the interior of the gear-housing 8 with grease. The open side of the gear-housing is closed by a plate 15.

As hereinbefore mentioned, the gear-housing 8 is supported solely by the bushing 8a and the screw 10, which arrangement simplifies the assembly of a machine incorporating the same. With this construction, it is possible to completely assemble the hook-shaft 11 and its gear 13, together with the hook 12 and other elements within the housing 8 as a sub-assembly, then position the same in place with the shaft 5 within the provided bore, and finally secure the same in place by the screw 10 and fixing the gear 14 to the end of the shaft 5. This construction facilitates manufacture as well as assembly since it makes it possible to drill the appropriate bores in the housing 8 by working on the easier-to-handle housing by itself rather than on the machine bed 1 which would be the case if the bores were formed in appropriate lugs depending from the bed.

The feed in the disclosed embodiment of the invention includes a feed-advance mechanism substantially as illustrated in the above patent of Eames to which reference may be had for a full description thereof. Briefly, the feed-advance mechanism includes a rock-shaft 16 journaled longitudinally of the bed 1 in suitable depending lugs 17 and 18. Oscillation is imparted to the rock-shaft 16 by a bar 19 that is connected thereto by a crank 20 (Fig. 1). The opposite end of the bar 19 pivotally and adjustably receives a rod 21 that is carried by a frame 22 secured to a countershaft 23 journaled in lugs 24 depending from the bed 1. The frame 22 includes a fork 25 that embraces an eccentric 26 on the shaft 5.

Thus, as the shaft 5 rotates, oscillation about the countershaft 23 is imparted to the frame 22, which through the rod 21, bar 19 and crank 20, oscillates feed-shaft 16. The bar 19 may be moved relative to the rod 21, as by the actuation of a link 27 connected to the bar at an intermediate point, in order to vary the amount of reciprocation of the bar 19 and thus to vary the oscillation of the shaft 16.

At its opposite end, the shaft 16 carries a feed-rocker 28, between the opposed arms of which is pivotally mounted one end of a feed-bar 29. The other end of the feed-bar 29 carries the feed-dog 30 which operates through the usual slots 31 in the throat-plate 2 to contact the work and to move the same past the stitching mechanism of the machine.

Feed-lift movements are imparted to the feed-dog 30 by an oscillating crank-arm 32 having a sliding block 33 fitted between the arms of a fork 34 that is formed as an integral portion of the feed-bar 29. The crank-arm 32 is secured to a feed-lift shaft or countershaft 35 journaled longitudinally of the bed 1 in depending lugs 36. A lever or pitman 37 is loosely mounted at one end on the countershaft 35 and at the other end is formed with a fork 38 that embraces an eccentric 39 on the shaft 5. The pitman 37 is provided with a transverse flange 40 intermediate its ends. A collar 41 is fixed to the countershaft 35 adjacent the pitman 37 which collar is provided with an arm 42 that underlies the flange 40 on the pitman 37. An enlarged bore 43 is formed in the arm 42 and an axially aligned threaded bore 44 is provided in the flange 40. A thumb-screw 45 having a head 46 passes loosely through the bore 43 and is threaded into the bore 44.

When the thumb-screw 45 is screwed into the bore 44, the head 46 is drawn against the arm 42 of the collar which is forced into engagement with the flange 40 on the pitman 37 and thus secured thereto as illustrated in Fig. 2. When so connected, the collar 41, which is secured to the countershaft 35, is coupled to the pitman and thus the pitman is coupled to the countershaft 35. Upon rotation of the shaft 5, the eccentric 39 will effect an oscillation of the pitman 37, which oscillation will be imparted to the countershaft through the flange 40, thumb-screw 45 and collar 41. Oscillation of the countershaft 35 will impart feed-lift motions to the feed-dog 30 through the crank 32 and feed-bar 29.

When the thumb-screw 45 is backed-off as illustrated in Fig. 5, the connection between the flange 40 and the arm 42 of collar 41, and, hence, the connection between the pitman 37 and the countershaft 35 is broken. In this condition, the pitman 37 will oscillate freely relative to the countershaft and will not impart its oscillation thereto, the screw 45 reciprocating freely within the enlarged bore of the arm 42. To insure that the feed-dog is retracted from its work-engaging position when the feed-lift mechanism is thrown out, there is provided a torsion spring 47 fitted within a counterbore of the collar 41, which spring surrounds the countershaft 35 and has its opposite ends embedded in the pitman 37 and the collar 41 as seen in Fig. 3. The spring 47 is tensioned to bias the collar 41 and thus the countershaft in that direction in which the feed-dog is urged downwardly from its operative position, or in a clockwise direction as viewed in Figs. 2 and 5. Downward movement of the feed-dog is limited by a stop-screw 48 threaded through a flange 49 of the loop-taker housing 8

which screw is in position to contact the feed-bar as it is urged downwardly by the spring 47.

Numerous alterations of the structure herein disclosed will suggest themselves to those skilled in the art. However, it is to be understood that the present disclosure relates to a preferred embodiment of my invention which is for purposes of illustration only and not to be construed as a limitation of the invention. All such modifications which do not depart from the spirit of the invention are intended to be included within the scope of the appended claims.

Having thus set forth the nature of the invention, what I claim herein is:

1. In a feeding mechanism for a sewing machine, a feed-lift shaft, a source of oscillation, and disconnectible means for operatively connecting said feed-lift shaft to said source of oscillation comprising a lever loosely pivoted coaxially of said feed-lift shaft and operatively connected to said source of oscillation, a flange on said lever, a collar fixed to said feed-lift shaft, an arm on said collar disposed adjacent to said flange, said flange and said arm having substantially axially aligned bores therein with the axes thereof arranged substantially parallel to the plane of oscillation of said lever, threads formed in a first one of said bores, and a shouldered threaded element extending loosely through the outer of said bores and operatively engaging the threads in said first one of said bores for disconnectibly coupling said lever to said arm.

2. In a feeding mechanism for a sewing machine, an actuating shaft, a feed-lift countershaft arranged substantially parallel to said actuating shaft and disconnectible means for operatively connecting said countershaft to said actuating shaft for oscillation of the former upon actuation of the latter, comprising, an actuating element fixed to said actuating shaft, a pitman freely pivoted coaxially of said countershaft and operatively engaging said actuating element to be oscillated thereby, a flange on said pitman, a collar fixed to said countershaft, an arm on said collar disposed adjacent to said flange, said flange and said arm having substantially axially aligned bores therein with the axes thereof arranged substantially parallel to the plane of oscillation of said pitman, threads formed in a first one of said bores, and a shouldered threaded element extending loosely through the other of said bores and operatively engaging the threads in said first one of said bores for disconnectibly coupling said pitman to said arm.

3. In a feeding mechanism for a sewing machine, a feed-lift shaft, a source of oscillation, and disconnectible means for operatively connecting said feed-lift shaft to said source of oscillation, comprising, a lever loosely pivoted coaxially of said feed-lift shaft and operatively connected to said source of oscillation, a flange on said lever, a collar fixed to said countershaft, an arm on said collar disposed adjacent to said flange, said flange and said arm having substantially axially aligned bores therein with the axes thereof arranged substantially parallel to the plane of oscillation of said lever, threads formed in a first one of said bores, a shouldered threaded element extending loosely through the other of said bores and operatively engaging the threads in said first one of said bores for disconnectibly coupling said lever to said arm, and resilient means for biasing said arm away from said flange.

4. In a sewing machine, an actuating shaft, a counter-shaft arranged substantially parallel to

said actuating shaft, a feed-bar, a crank secured to said countershaft and operatively connected to said feed-bar for imparting feed-lift movements thereto upon oscillation of said countershaft and said crank, disconnectible means for operatively connecting said countershaft to said actuating shaft for oscillation of the former upon actuation of the latter, comprising, an actuating element fixed to said actuating shaft, a pitman freely pivoted coaxially of said countershaft and operatively engaging said actuating element to be oscillated thereby, a flange on said pitman, a collar fixed to said countershaft, an arm on said collar disposed adjacent to said flange, said flange and said arm having substantially axially aligned bores therein with the axes thereof arranged substantially parallel to the plane of oscillation of said pitman, threads formed in a first one of said bores, and a shouldered threaded element extending loosely through the other of said bores and operatively engaging the threads in said first one of said bores for disconnectibly coupling said flange to said arm.

5. In a sewing machine having a bed, a rotary hook-actuating shaft journaled longitudinally of said bed, a feed-lift countershaft journaled longitudinally of said bed and arranged substantially parallel to said hook-actuating shaft, a feed-bar, a crank secured to said countershaft and operatively connected to said feed-bar for

imparting feed-lift movements thereto upon oscillation of said countershaft and said crank, disconnectible means for operatively connecting said countershaft to said hook-shaft for oscillation of the former upon rotation of the latter comprising an actuating element fixed to said hook-actuating shaft, a pitman freely pivoted coaxially of said countershaft and operatively engaging said actuating element to be oscillated thereby, a flange on said pitman, a collar fixed to said countershaft, an arm on said collar disposed adjacent to said flange, said flange and said arm having substantially axially aligned bores therein with the axes thereof arranged substantially parallel to the plane of oscillation of said pitman, threads formed in a first one of said bores, and a shouldered threaded element extending loosely through the other of said bores and operatively engaging the threads in said first one of said bores for disconnectibly coupling said flange to said arm.
